UNITED STATES PATENT OFFICE.

HOWARD S. ROBBINS, OF NEW YORK, N. Y., ASSIGNOR TO FREDERICK DENT GRANT, TRUSTEE.

DESIGN FOR A BADGE.

SPECIFICATION forming part of Design No. 26,722, dated March 9, 1897.

Application filed January 20, 1897. Serial No. 619,987. Term of patent 14 years.

To all whom it may concern:

Be it known that I, HOWARD S. ROBBINS, a citizen of the United States, residing in the city, county, and State of New York, have 5 invented and produced a new and original Design for a Badge, of which the following is a specification, reference being had to the accompanying drawing, forming part thereof.

The leading features of my design for a 10 badge are, first, the obverse of the body of the badge consisting of a serrated star, a cross thereon, a wreath on said cross, and a hel- meted head within said wreath; next, the re- 15 verse of the body consisting of a many-pointed star imposed on the star of the obverse, and a seal composed of an annular band and an eagle, said seal being on the many-pointed star; finally, a ribbon gathered in the center by a ring, a star on said ring, and a wreath 20 depending from the latter, said wreath rising from the body of the badge.

The figure represents the obverse and re- 25 verse of a badge embodying my design.

In the drawing, A designates the body of the badge, composed of the serrated star B, on the face of the obverse of which is the cross

C, the wreath D, and the helmed head or bust E within said wreath. On the reverse on the serrated star B is a smaller many-pointed star F and a seal on said star F, the 30 same being composed of the annular band G and the eagle H within the latter.

J designates a suspension device for the body of the badge, the same consisting of the ribbon K, the ring L gathering the center of 35 said ribbon, the star M on the front of said ring, and the wreath N pendent from the latter.

What I claim is—

1. In the design for a badge, the obverse 40 substantially as shown and described.
2. In the design for a badge, the reverse substantially as shown and described.
3. In the design for a badge, a suspension device of the form substantially as shown. 45
4. The design for a badge, substantially as described and shown.

HOWARD S. ROBBINS.
